UNITED STATES PATENT OFFICE.

JOSEPH A. DEDOUCH, OF OAK PARK, ILLINOIS.

CONTINUOUS CERAMIC FURNACE.

Application filed April 22, 1927. Serial No. 185,735.

This invention relates to continuous ceramic furnaces, and the like, particularly of the muffle type, and is fully described in the following specification and shown in the accompanying drawings in which:

Figure 1 is a longitudinal elevation of the furnace showing the heating-chamber in section;

Fig. 2 is a perspective view of the furnace proper showing the upper portion in raised position;

Fig. 3 is a broken section on the broken line 3—3 of Fig. 2;

Fig. 4 is an enlarged longitudinal section of the coupling for securing the ends of the wire conveyor;

Fig. 5 is a top plan view of a modified form of the furnace; and

Fig. 6 is a side elevation of the same.

The embodiment shown in Figs. 1 to 3 inclusive comprises a small enamelling furnace consisting essentially of upper and lower furnace-sections 10 and 11 having a muffle-chamber 12 extending longitudinally there-through together with a conveyor consisting of two or more parallel wires 13 extending through this muffle-chamber and passing over pulleys 14 and 15 which are geared together by means of a chain 16 and suitable sprockets

17. The pulley 14 is driven by means of a sprocket 18 and a chain 19 from the sprocket 20 which is suitably geared to a motor 21, or other suitable source of power. The wire 13 is continuous and is crossed on the lower strand 13^a and is held in suitable guides 13^b and runs over a grooved roller 13^c for spacing the wires 13. An anti-friction mounting is used for the roller 13^c.

The furnace proper consists of upper and lower sections 10 and 11, each section being hollow and provided with lateral openings 10^a and 11^a which are in registration with the fuel-burners 10^b and 11^b when the upper section is in the lowered position.

In Figs. 2 and 3, however, the upper section is shown in the raised position.

The lower section is carried upon a frame 22 which carries a bracket 23 upon which is pivotally mounted a lever 24, the end of which engages an eye 25 which is carried by a frame 26 which, in turn, carries the upper furnace-section 10. Clips 27 on the upper furnace-section 10 are slidable upon guides

28 carried by the lower section so as to guide the upper section when it being raised and lowered.

The lower section has a heating-chamber 29 which has an opening 30 which registers with an opening 31 (Fig. 3) in the upper section when the upper section is in lowered position.

In operation, the furnace is lighted and heated to the desired temperature. During this time, the pulleys 14 and 15 are set in operation so as to keep the wire 13 in motion through the furnace so that it will not become unduly heated at one point. This wire is preferably of nichrome steel and keeps its rigidity even when red hot.

In Fig. 4 is shown a coupling 32 slightly larger than the wire 13 and having an opening 33 at one side near its center. The ends of the wire 13 are pushed through the tube 32 which is slightly larger than the wire itself. These ends are then upset, or riveted, at 13^a 75 so as to prevent their withdrawal from the tube 32. Owing to the fact that the opening is slightly larger than the wire a certain amount of flexibility is permitted. This coupling has been found to meet the difficult 80 conditions under which the wire operates in this furnace.

After the furnace has attained the desired temperature, small articles to be glazed or enamelled are placed upon the wires 13. 85 which carry them through the muffle-chamber 12 of the furnace and the speed of the wires is such as to subject them to the desired temperature for the required length of time to complete the enamelling operation. As 90 they pass out of the furnace, they are removed from the wires 13. Thus, in passing through the furnace, the articles to be enamelled do not come in contact with any parts of the furnace other than the wires 13 on which 95 they rest.

In Figs. 5 and 6 is shown a modified form of the furnace in which 34 and 35 are furnaces which may be of the type described. Through these pass parallel metal bands 36 100 and 37 which overlie each other and which pass over the pulleys 38 and 39. The band 37 lies outside the band 36 on the flanged pulleys 38 and 39 and is separated therefrom by means of pulleys 37^a. Where the work to be 105 carried is quite light, the driving may be

done entirely by the pulley 38, the pulley 39 serving merely as an idler. If desired, these two may be geared together as by means of sprockets and a chain as was described in connection with the furnace shown in Fig. 1. The parallel bands 36 and 37 are also preferably of nichrome steel and are made quite thin so that the difference in radius when passing around the pulleys will not be great enough to make much difference in their speeds as they pass through the furnace. This difference is so slight as to be practically negligible. These bands, however, are quite deep so as to add stiffness. In this way, articles of considerable weight may be carried by these parallel bands through the furnace.

It will also be obvious that flat bands like 37 may be run over the horizontal pulleys 14 and 15 if desired. This may be preferable for certain kinds of work.

Thus, it will be seen that a very simple and efficient form of furnace is provided and one which is capable of being modified to adapt it for a wide range of uses.

The pulley 15 is mounted on supports 50 carried on a slideable base 51 adapted to be adjusted horizontally by the adjusting screw 52 working through the nut 53. Such horizontal adjustment of the base 51 on which the pulley 15 is mounted provides takeup means to take up the slack in the conveyor elements and the chain 16.

While I have shown and described but a few embodiments, it is to be understood that it is capable of many modifications. Changes, therefore, in the arrangement and construction may be made which do not depart from the spirit and scope of the invention as disclosed in the appended claims in which my invention is to claim the invention as broadly as possible, in view of the prior art.

I claim:

1. In combination, a ceramic furnace having a heating chamber, and parallel conveyor elements, having a flat cross-section, the long axis of the section being vertical, movable through said heating chamber at substantially the same speed for carrying objects to be fired.

2. In combination, a ceramic furnace having a straight horizontal heating chamber having two sections divided horizontally, means for readily lifting the upper section, and parallel conveyor elements movable through said heating chamber at substantially the same speed for carrying objects to be fired.

3. In combination, a ceramic furnace having a heating chamber, and parallel conveyor elements movable through said heating chamber at substantially the same speed for carrying objects to be fired, said conveyor elements being unsupported within said furnace.

4. In combination, a ceramic furnace having a heating chamber, and an integral con-

tinuous parallel conveyor element having a plurality of turns movable through said heating chamber at substantially the same speed for carrying objects to be fired.

5. In combination, a ceramic furnace having a heating chamber composed of two sections divided horizontally, a lever for raising and lowering the upper section, pulleys at opposite ends of said furnace, and flexible parallel conveyor elements passing around said pulleys and driven thereby, said elements passing through said heating chamber at substantially the same speed for carrying objects to be fired.

6. In combination, a ceramic furnace having a heating chamber, pulleys at opposite ends of said furnace, flexible one-piece integral parallel conveyor elements passing around said pulleys and driven thereby, said elements passing through said heating chamber at substantially the same speed for carrying objects to be fired, and means for driving both said pulleys.

7. In combination, a ceramic furnace having a heating chamber, pulleys at opposite ends of said furnace, flexible one-piece integral parallel conveyor elements passing around said pulleys and driven thereby, said elements passing through said heating chamber at substantially the same speed for carrying objects to be fired, and take-up means on one of said pulleys.

8. In combination, a ceramic furnace having a heating chamber, pulleys at opposite ends of said furnace, and flexible parallel conveyor elements passing around said pulleys and driven thereby, said elements passing through said heating chamber at substantially the same speed for carrying objects to be fired, said elements being unsupported between said pulleys.

9. In combination, a ceramic furnace divided into two sections along a horizontal plane and having a longitudinal passage therethrough, a conveyor adapted to carry articles to be fired through said passage, and means for raising the upper section of the furnace to permit inspection of work resting on the conveyor.

10. In combination, a ceramic furnace divided into two sections along a horizontal plane and having a longitudinal passage therethrough, a conveyor adapted to carry articles to be fired through said passage, and means for raising the upper section of the furnace to permit inspection of work resting on the conveyor, said furnace being of the muffle type.

11. In combination, a ceramic furnace divided into two sections along a horizontal plane and having a longitudinal passage therethrough, a conveyor adapted to carry articles to be fired through said passage, and means for raising the upper section of the furnace to permit inspection of work resting

on the conveyor, said furnace being of the muffle type, the muffle chambers of the upper and lower sections being connected by one or more passages which register when the 5 upper section is lowered.

12. In a ceramic furnace, a furnace chamber having a longitudinal passage there-

through, a continuous integral flexible conveyor element adapted to carry work through said furnace. 10

In testimony whereof I have hereunto set my hand this 19th day of April, 1927.

JOSEPH A. DEDOUCH.
